FUEL INJECTION NOZZLE

Einar S. Dahl, Decatur, Ill., assignor to Borg-Warner Corporation, Chicago, Ill., a corporation of Illinois

Filed Feb. 4, 1959, Ser. No. 791,217

7 Claims. (Cl. 239—453)

This invention relates to a spray type fuel injection nozzle particularly adapted to inject fuel into the air intake manifold of an internal combustion engine.

It is an object of the present invention to provide a fuel injection nozzle that is simple in construction, inexpensive to manufacture, and uniformly reliable in performance.

It is another object to provide a fuel injection nozzle that is easily assembled and calibrated for a desired opening pressure and adapted for mass production methods of manufacture.

More particularly, it is an object of the present invention to provide a nozzle that is finally assembled and calibrated for a desired opening pressure by one simple external operation.

It is a more particular object to provide a fuel injection nozzle having a cylindrical body or tube, a spring loaded valve stem, a nozzle tip, and a double screw advance mechanism for simultaneously mounting the nozzle tip and valve stem within the tube and adjusting the opening pressure of the valve stem.

The invention consists of the novel constructions, arrangements, and devices to be hereinafter described and claimed for carrying out the above stated objects and such other objects as will appear from the following description of a preferred form of the invention, illustrated with reference to the accompanying drawings wherein:

Fig. 1 is a longitudinal sectional view of the improved fuel injection nozzle of the present invention; and

Figs. 2, 3, and 4 are views taken respectively on lines 2—2, 3—3, and 4—4 of Fig. 1.

Like characters of reference designate like parts in the several views.

Referring now to Fig. 1, the improved fuel injection nozzle of the present invention is designated generally by the numeral 10. The nozzle 10 comprises a cylindrical tube or body 11, a nozzle tip 12, a valve stem 13, a spring 14, and a spring seat 15. The nozzle tube 11 is formed with a longitudinal fuel passage comprising a central cylindrical bore 16, a relatively larger connected bore 17 on one end for receiving the nozzle tip 12, and a still larger connected bore 18 on the other end for connecting the nozzle 10 to a fuel supply line.

The bore 16 is threaded on its interior at 19 with a screw thread of relatively large pitch. The bore 17 is threaded on its interior at 20 with a screw thread of a relatively smaller pitch. The spring seat 15 is generally cylindrical in shape and is formed on its exterior with threads 21 adapted to mesh with the threads 19. The nozzle tip 12 is also generally cylindrical in shape and is formed on a portion of its exterior with threads 22 adapted to mesh with the threads 20. The spring seat 15 is also formed with an axial central bore 23 and external parallel flat surfaces 24. The nozzle tip 12 is formed with a transverse slot 25 which receives the flat surfaces 24 of the spring seat 15. The nozzle tip 12 is also formed

with an axial central bore 26 through which the valve stem 13 extends, an external annular groove 27 for receiving an O ring 28, and two longitudinal grooves 29. The central bore 26 is flared at 30 so as to form a seat for the valve stem 13.

The valve stem 13 is formed with an integral hemispherical head 31 on one end and an integral cylindrical collar 32 on the other end thereof. The hemispherical head 31 is adapted to form a fluid tight seal against the seat 30 of the nozzle tip 12. The head 31 is also formed with a flared outer edge or skirt 33 which defines a constant spray angle for the fuel discharged by the nozzle 10.

A spring retaining cap 34 is provided with a cylindrical recess 35 for receiving the collar 32 and a radial slot 36 for embracing the valve stem 13. The spring 14 surrounds the valve stem 13 and is disposed under compression between the retaining cap 34 and a cylindrical recess 37 formed in the spring seat 15.

The nozzle 10 also includes a screen strainer 38, a filtering felt 39, and a spring 40 for retaining the felt 39 within the bore 18. The bore 18 is threaded on its interior at 41 for connecting the nozzle to a fuel supply line.

In assembling the nozzle for use, the O ring 28 is placed in the annular groove 27 of the nozzle tip 12 and the valve stem 13 is inserted through the central bore 26 of the nozzle tip 12 and through the central bore 23 of the spring seat 15. The spring 14 is placed on the valve stem 13 over the collar 32 is compressed slightly, and the retaining cap 34 is inserted radially with the slot 36 engaging the valve stem 13. The spring 14 is then released and it forces the retaining cap axially so that the collar 32 enters the recess 35 and the head 31 is forced against the seat 30.

The nozzle tip 12, valve stem 13, spring 14, and spring seat 15 are now ready for assembly as a unit into the tube 11. The valve stem 13 is inserted into the nozzle tube 11 with the collar 32 first so that the threads 21 of the spring seat 15 engage the threads 19 within the bore 16, and the threads 22 engage the threads 20 within the bore 17.

A spanner type wrench having radial teeth that engage the longitudinal slots 29 is utilized for turning the nozzle tip 12 within the tube 11. As the nozzle tip 12 is turned clockwise, the turning torque is transmitted through slot 25 and flat surfaces 24 so as to turn the spring seat 15 as well. The difference in pitch of the threads 21 and 22 causes the spring seat 15 to advance at a greater rate than the nozzle tip 12, thereby compressing the spring 14. The nozzle body 11 may be screwed onto a source of fluid pressure, and the nozzle tip 12 can be turned within the nozzle tip 11 compressing the spring 14 until a desired opening pressure for the valve head 31 is obtained. The screen 38, felt 39, and spring 40 are inserted and the nozzle is completely assembled and ready for use.

The O ring 28 functions both as a seal and as a locking member for locking the position of the nozzle tip 12 within the tube 11. If desired, the end of the nozzle tube 11 can be crimped into the longitudinal grooves 29 to insure that the angular position of the nozzle tip 12 with respect to the tube 11 does not change.

There has been provided by this invention a fuel injection nozzle that is inexpensive, simple in construction, and easily assembled and calibrated for a desired opening pressure. Nozzles produced according to this invention will be uniform in performance and operating characteristics and should require no further adjustment or calibration for operation in a fuel injection system.

It is to be understood that this invention is not to be limited to the specific constructions and arrangements shown and described except only insofar as the appended

claims may be so limited, as it will be apparent to those skilled in the art that changes may be made without departing from the principles of the invention.

I claim:

1. In a fuel injection nozzle having a tubelike body, a nozzle tip adjustably mounted within the body, a valve disposed within said nozzle tip and a spring for holding said valve in a fluid sealing position against said tip, the combination of spring adjusting means adapted to be adjustably mounted within the body, means for mounting the nozzle tip within said body, and differential motion transmitting means drivingly interconnecting said nozzle tip with said spring adjusting means for establishing a reaction force within said spring whereby the opening pressure of the valve may be calibrated by the same operation as that by which the nozzle tip is mounted within the body.

2. In a fuel injection nozzle, the combination of a tubelike body formed with a longitudinal fuel passage therethrough, a nozzle tip adapted to be adjustably mounted within the body and also formed with a fuel passage therethrough, a valve disposed within the fuel passage of said nozzle tip and adapted to form a fluid-tight seal on one end thereof, a spring acting on said valve for maintaining it in fluid sealing position below some predetermined opening pressure, spring adjusting means also adapted to be mounted within said body, means for drivingly interconnecting said spring adjusting means with said nozzle tip, and means for advancing said spring adjusting means at a greater rate than said nozzle tip is advanced when mounting the nozzle tip within said body, whereby the opening pressure of said valve can be calibrated by adjustment of said nozzle tip.

3. In a fuel injection nozzle, the combination of a tubelike body having a longitudinal fuel passage therethrough to one end of which fuel under pressure is adapted to be supplied, a threaded nozzle tip formed with a fuel passage defining a valve seat on one end thereof and adjustably threaded within said body, a valve extending into said fuel passages, spring means attached to said valve for forcing it against said seat, and threaded spring adjusting means interconnected with said nozzle tip and said spring and adapted to be threaded within said body, the threads of said adjusting means being of a different pitch than the threads of said nozzle tip for thereby imparting a differential motion to said adjusting means as said tip is threaded within said body whereby the opening pressure of said valve can be calibrated by external adjustment of said nozzle tip.

4. In a fuel injection nozzle, the combination of a tubular body having a longitudinal fuel passage that is threaded on its interior with first threads on a relatively large pitch and with second threads of a comparatively smaller pitch; a spring seat comprising a sleeve-like body formed on its exterior with threads of comparatively large pitch for engaging said first threads of said body; a nozzle tip formed with a longitudinal fuel passage therethrough and threads on its exterior of comparatively small pitch for engaging said second threads of said body; means for drivingly connecting said nozzle tip to said spring seat; a valve extending through the fuel passage of said nozzle tip and adapted to form a fluid-tight seal on one end thereof below some predetermined opening pressure; and a spring surrounding said valve and disposed under compression between said spring seat and an inner end of said valve, whereby said spring seat and said nozzle tip can be threaded simultaneously within said nozzle body with said spring seat advancing at a greater rate than said nozzle tip for thereby compressing

said spring and adjusting the opening pressure of said valve as said nozzle tip is threaded within said body.

5. In a fuel injection nozzle, the combination of a tubelike body member having a longitudinal fuel passage therethrough that is formed throughout a portion of its length with threads of relatively large pitch, said passage also being enlarged at one end of the body and threaded on its interior with threads of comparatively smaller pitch; a nozzle tip formed with a fuel passage therethrough and threaded on its exterior for a portion of its length, said nozzle tip also being formed with a transverse slot on an inner end thereof; means defining a valve seat on the outer end of said nozzle tip fuel passage; a valve extending through said nozzle tip and adapted to form a fluid-tight seal against said seat; spring means surrounding said valve for forcing said valve against said seat; and a spring compression adjusting seat comprising a sleeve-like member formed on its exterior with threads of comparatively large pitch and external parallel flat surfaces adapted to engage the transverse slot of said nozzle tip, said spring adjusting seat and said nozzle tip being adapted to be threaded simultaneously into said nozzle body with the threads of said spring seat engaging said first named threads and the threads of said nozzle tip engaging said last named threads with said spring seat advancing at a greater rate than said nozzle tip for thereby compressing said spring as said nozzle tip is threaded into said body.

6. In a fuel injection nozzle, the combination of a tubelike body having a longitudinal fuel passage therethrough, a nozzle tip formed with a fuel passage defining a seat on one end thereof and adjustably mounted within said body, a valve extending into said fuel passage and adapted to form a fluid-tight seal against said seat below some predetermined opening pressure, spring means connected to said valve for forcing it against said seat, spring adjusting means mounted within said body and adapted to act on said spring, and differential motion transmitting means interconnecting said nozzle tip and said spring adjusting means whereby the force of said spring means and opening pressure of said valve can be adjusted by external adjustment of said nozzle tip.

7. In a liquid spray type nozzle, the combination of a tubelike body having a longitudinal liquid passage therethrough and to one end of which liquid under pressure can be supplied, a nozzle tip adjustably mounted within said body and formed with a longitudinal liquid passage defining a valve seat on one end thereof, a valve extending into said passage and adapted to form a fluid-tight seal against said seat below some predetermined opening pressure, adjustable spring means acting against said valve and effective to determine the opening pressure thereof, spring adjusting means mounted within said body and interconnected with said nozzle tip and acting on said spring means, and differential motion transmitting means forward integrally with said nozzle tip and said spring adjusting means whereby the opening pressure of said valve can be calibrated by external adjustment of said nozzle tip.
